CERVICAL SCRAPER

James Ernest Ayre, Miami, Fla., assignor to Clay-Adams,
Inc., New York, N.Y., a corporation

Filed Feb. 12, 1962, Ser. No. 68,758

Term of patent 14 years

(Cl. D83—12)

FIG.4

FIG.5

FIG. 1 is a front elevational view of a cervical scraper showing my new design, the rear being a mirror image thereof;

FIG. 2 is a side elevational view thereof, looking at the left side of FIG. 1;

FIG. 3 is a side elevational view thereof, looking at the right side of FIG. 1;

FIG. 4 is an end elevational view thereof, looking at the top edge of FIG. 1; and

FIG. 5 is an end elevational view thereof, looking at the bottom edge of FIG. 1.

I claim:

The ornamental design for a cervical scraper, as shown and described.
